WATCH CASE

Giuseppe Montese-Caruso, Viale Blanca Maria 22,
Milan, Italy

Filed Nov. 27, 1962, Ser. No. 72,630

Term of patent 14 years

(Cl. D42—8)

FIG. 1

FIG. 3

FIG. 1 is a top perspective view of a watch case showing my new design;

FIG. 2 is a bottom perspective view thereof; and

FIG. 3 is a side elevational view thereof in partial cross-section.

The essential features of my design reside in the portions shown in full lines.

I claim:

The ornamental design for a watch case, as shown and described.
